UNITED STATES PATENT OFFICE.

HIRAM C. FENTON, OF HARTFORD, CONNECTICUT, ASSIGNOR OF ONE-HALF
TO GEORGE C. EMERSON, OF SAME PLACE.

BENCH-CLAMP.

SPECIFICATION forming part of Letters Patent No. 322,434, dated July 21, 1885.

Application filed June 1, 1885. (No model.)

To all whom it may concern:

Be it known that I, HIRAM C. FENTON, of Hartford, in the county of Hartford and State of Connecticut, have invented certain new and useful Improvements in Bench-Clamps, of which the following is a description, reference being had to the accompanying drawings, where—

Figure 1 is a bottom view of my improved clamp. Fig. 2 is a side view of the same, shown as attached to a bench. Fig. 3 is a view in horizontal section through the clamp on plane denoted by line $x-x$ of Fig. 2.

The object of my invention is to provide a bench-clamp of simple and cheap construction adapted to be secured to the under side of a bench, seat, or like structure, for firmly holding a removable tool or the like; and my improvement consists in the body or holder of the clamp, cast to shape, with a tool-socket extending completely through it, and a second socket within the body and crossing the first, in which is located a movable clamping-arm bearing means for operating it, as more particularly hereinafter described.

In the accompanying drawings, the letter a denotes the body of the clamp, preferably made of metal, cast to shape, with the flanges a' a'' , projecting from the sides of the body near and in the plane of its side, adapted to rest against the structure to which it is to be secured, and through these flanges are screw-holes, whose use is obvious. At right angles to the bearing-surface of the body is a perforation, b , preferably cylindrical, and at about the center of the body is a transverse clamp-socket, c , with the narrow part c' adapted to contain the broader part of the clamp d , while the stem d' extends past the hole b and projects sufficiently beyond the farther side of the body a as to afford space for supporting the lever e . This lever e is pivoted upon the stem of the clamp, and held against outward play on it by means of a nut or like device, and it bears on the face next to the body of the clamp one or more cams, e' , that co-operate with cams e'' formed upon the body of the clamp, which cams are so

arranged that by depressing the lever the 50 grasping-face d'' of the hooked arm of the clamp is pulled toward the hole b in such manner as to firmly grasp the stem or spindle f of any tool that may be thrust through the hole.

This clamp as a whole is adapted to be secured to the under side of a bench or like structure so that the hole b registers with a hole through the bench, so that the shanks of a bench-hook or other tool that is to be 60 used upon the upper surface of the bench may be thrust through the hole into the body of the clamp, and held firmly by means of the clamping-lever already described, it being understood that the shank of such tool or the 65 handle of the article shall be of a size adapted to fit quite closely within the hole b in the body of the clamp.

This clamp-body, with its respective flanges, openings, and cams, is formed in a single casting, and the clamp is inclosed wholly within the body of the structure.

I am aware that similar clamp devices, having parts adapted to be brought together forcibly by means of a lever bearing cam-faces, are not new, and such I do not, broadly, claim.

I claim as my invention—

1. In combination with the clamp body a , having flanges a' a'' , vertical socket b , and transverse clamp-socket c and the cams, all cast in one piece, the hook-shaped clamp d , located within the clamp-socket c , with its broader part bearing the grasping-face d'' and its stem d' bearing the cam-lever e , all substantially as described.

2. In combination with the clamp-body a , having the vertical socket b , the transverse clamp-socket c , opening into the other and bearing on an outer side the cams c' , the hook-shaped clamp d , located within the clamp-socket, with its broader part having the grasping-face d'' and its stem d' bearing the cam-lever e , all substantially as described.

HIRAM C. FENTON.
